(74) Attorney, Agent, or Firm — True Shepherd, LLC;
Andrew Cheng(57) CLAIM

The ornamental design for an air purifier, as shown and described.

DESCRIPTION

FIG. 1 is a front, right and top perspective view of an air purifier, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the air purifier that form no part of the claimed design.
